Primary Examiner — Ian Simmons*Assistant Examiner* — Keith Frank(74) *Attorney, Agent, or Firm* — Alston & Bird LLP(57) **CLAIM**

The ornamental design for a flask and cap assembly, as shown and described.

DESCRIPTION

FIG. 1 is a top view of a flask and cap assembly according to the present invention;

FIG. 2 is a perspective view of the flask and cap assembly according to FIG. 1;

FIG. 3 is a front view of the flask and cap assembly according to FIG. 1; and,

FIG. 4 is a side view of the flask and cap assembly according to FIG. 1.
